Percentage Feeder
Fred Keeney, Portsmouth, Va.
Application Oct. 27, 1943, Serial No. 507,917
2 Claims. (Cl. 222—311)

This invention relates to a machine designed for use in feeding, delivering or discharging an extremely variable amount of pulverized, semi-coarse or whole-grain materials.

A primary object of the invention is to provide a machine of this character which may be adjusted to various settings, depending on the amount of material to be delivered, the adjustment being such as to allow a great number of settings, between the minimum and maximum of the feeding capacity of the machine.

Still another object of the invention is to provide a machine of this character which will cause the material under treatment, to be formed into a layer on the rotating cone or disk, there being provided adjustable slides adapted to contact with the material, spreading the material over the cone or disk in layers of various degrees of thickness.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings

Fig. 1 is a front elevational view of a percentage feeding machine, constructed in accordance with the invention.

Fig. 2 is a vertical sectional view through the machine.

Fig. 3 is a plan view of the machine.

Fig. 4 is a sectional view taken on line 4—4 of Fig. 2.

Referring to the drawings in detail, the reference character 5 designates the base of the machine from which the supporting plates 6 rise, the supporting plates 6 being held in spaced relation with respect to each other, by means of the horizontal plate 7, which is shown as having its ends connected to the plates 6. This horizontal plate 7 provides a bearing for the vertical shaft 8 which extends into the body portion of the machine, as clearly shown by Fig. 2 of the drawings.

The power shaft of the machine is indicated by the reference character 9 and is provided with a pinion 10 that meshes with pinion 11 secured to the lower end of the shaft 8, whereby rotary movement of the shaft 9 is transmitted to the shaft 8.

Mounted on one end of the shaft 9, is a pulley 12 over which a belt not shown, and which oper-

ates over a suitable power pulley not shown, may operate, to rotate the shaft 9.

The body portion of the machine is indicated generally by the reference character 13, and includes a bottom 14, which is hollowed out slightly, so that material passing onto the bottom, will be retained in the hollowed out portion.

Secured on the upper end of the shaft 8, is the delivery disk 15, which is curved downwardly from the center thereof, the periphery of the disk being spaced slightly from the inner surface of the body 13, so that material under treatment will not become wedged or packed between the disk and wall of the body 13.

Vertical blades 16 extend downwardly from the feed disk 15, and operate in the hollowed-out portion of the bottom 14 acting as scrapers to remove material which may find its way into the hollowed-out portion of the bottom 14.

The wall of the body at the front thereof, is cut away, providing a discharge opening at 17, so that material which falls onto the feed disk 15, will be fed from the machine under the centrifugal force of the feed disk 15.

The reference character 18 designates a partition which extends inwardly from the wall of the body 13, to a point at the center of the body. Another partition 19 connects with the partition 18 and extends at an oblique angle with respect to the partition 18, from the center of the body to the discharge opening thereof. The connection between the partitions 18 and 19, forms a vertical guideway in which one edge of the vertical partition 20 slides, the opposite edge of the vertical

partition 20 moving in the guide 21 which is secured to the inner surface of the body 13. Rack bars 21 are secured to the surface of the vertical partition 20, adjacent to the opposite side edges thereof, which rack bars cooperate with the pinions 22, carried on the shaft 23 that is mounted in bearings 24 mounted on the top 25 of the body portion. A handle 26 is formed on one end of the shaft 23, whereby the shaft 23 may be rotated to adjust the vertical partition 20, so that the lower edge thereof may be moved to various positions in spaced relation with the feed disk 15.

As clearly shown by Fig. 1 of the drawings, the partition 20 is formed with a cut-out portion extending upwardly from the lower edge thereof, to a point substantially one-quarter of the length of the partition, providing a discharge opening. Guides 27 are secured to the vertical partition, adjacent to the cut-away portion, in which the slide valve 28 is mounted, which slide valve may be operated to close the opening of the vertical

partition 20, or partially close the same as desired, to insure a predetermined quantity of material being discharged from the machine.

In order that the adjustment of the slide valve 28 may be accurately formed, graduations are provided on the partition 20, adjacent to one edge of the slide valve. An indicating finger is formed on the slide valve and cooperates with the graduations in indicating the distance the valve is open.

The upper end of the slide valve 28 is extended laterally and is formed with a threaded opening to receive the threaded shank 29, which extends through an opening in the inturned end 30 of the partition 20, the shank 29 being provided with a hand-wheel 31, whereby the adjustment of the slide valve 28 may be made readily.

The reference character 31' designates a horizontal shaft that extends through the body of the machine, the shaft 31' being provided with fingers 32, that extend laterally therefrom, and which fingers operate to agitate material in the body to prevent the material from packing.

A pulley 33 is mounted on one end of the shaft 31', and receives motion from the main shaft 9 of the machine, through the belt 34, which operates over the pulley 33, and pulley 35, secured to one end of the shaft 9.

Mounted at the front of the machine, directly under the discharge opening of the body portion, is a delivery hopper 36 from which the spouts 37 and 38 extend, there being provided a valve member 39, within the hopper, which may be moved to direct material from the hopper to either spout 37 or 38, to facilitate the delivery of the material to bags or receptacles being filled with the material.

In the operation of the machine, material is fed into the body portion, where it falls onto the feed disk 45. The feed disk being constantly rotated, discharges the material, due to centrifugal force, into the hopper 36 where it is carried through the spout 37 or 38 to a place of deposit.

By adjusting the vertical partition 20 and the slide valve 28, the thickness of the material carried through the open side of the hopper, may be regulated, to the end that a predetermined percentage of a certain material of a mix, may be insured.

What is claimed is:

1. In a device of the class described, a body portion having a discharge opening in the wall thereof, a partition within the body portion dividing the body portion into a receiving compartment and a feed compartment, said partition having an opening through which material passes from the receiving compartment to the feed compartment, a vertically movable main valve member mounted on the partition and adapted to move over the opening of the partition, regulating the quantity of material fed through the feed compartment, said main valve member having an opening through which material passes, a second slide valve mounted on the main valve member and being movable over the opening of the main valve member, regulating the quantity of material delivered to the feed compartment, and a rotary feed disk operating in the body portion and adapted to deliver material from the feed compartment.
2. In a device of the class described, a body portion having a discharge opening in the wall thereof, a rotary disk operating at the bottom of the body portion and on to which material is fed, a substantially wide vertically movable partition dividing the body portion into a receiving compartment and a delivery compartment, the lower edge of the vertically movable partition being spaced from the surface of the disk, whereby material may pass under the partition, means for moving the partition vertically, regulating the space between the lower edge of the partition and disk, said partition having an opening disposed intermediate its side edges and extending upwardly from the lower edge thereof, a substantially narrow slide valve member mounted on the partition and adapted to move over said opening, regulating the size of said opening, means for moving the slide valve member with respect to the partition whereby the quantity of material transferred from the receiving compartment to the delivery compartment may be regulated, and said disk adapted to direct material through the discharge opening of the body portion as it rotates.

FRED KEENEY.
